UNITED STATES PATENT OFFICE.

MINOT C. BLEST, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

DISCHARGE-DOOR-OPERATING MECHANISM.

1,267,363.

Specification of Letters Patent. Patented May 28, 1918.

Application filed October 30, 1917. Serial No. 199,291.

To all whom it may concern:

Be it known that I, MINOT C. BLEST, a citizen of the United States, residing at No. 624 Orchard avenue, Bellevue, in the county 5 of Allegheny and State of Pennsylvania, have invented certain new and useful Improvements in Discharge-Door-Operating Mechanism, of which the following is a specification.

10 An object of the invention is to provide fluid pressure actuated means for automatically operating the discharge doors of a railway car.

Another object of the invention is to provide fluid pressure actuated means for automatically unlocking and operating the discharge door mechanism of a railway car.

Another object of the invention is to provide means where the discharge doors of a 20 railway car may be operated either by hand or automatically by fluid pressure.

Another object of the invention is to provide fluid pressure means for operating a plurality of pairs of discharge doors either 25 simultaneously or separately.

Another object of the invention is to provide a discharge door operating mechanism for railway dump cars having a plurality of pairs of operatively connected motors, one 30 of the motors of each pair being constructed so as to operate in advance of and time the action of the other motor of each pair.

Another object of the invention is to provide a novel locking mechanism for discharge door operating mechanisms, which 35 may be operated either by hand or fluid pressure, and is so constructed as to eliminate the use of the usual ratchet and pawl mechanism, thus reducing to a minimum 40 the number of parts which are likely to wear or become damaged.

Referring now to the drawings in which like reference characters refer to like parts; Figure 1 is a plan view of one half of a car 45 embodying the invention; Fig. 2 is a side elevational view of the same, and Fig. 3 is an enlarged cross sectional view taken on the line 3—3 of Fig. 2. Fig. 4 is an enlarged plan view of a portion of one end of 50 the car with portions of the body removed to more clearly show the discharge door operating mechanism, Fig. 5 is an enlarged sectional view taken on the line 5—5 of Fig. 2; Fig. 6 is an enlarged elevational view of

the locking mechanism, and Fig. 7 is a plan 55 view of portions of the piping for the discharge door operating mechanism, one of the pipes being broken away to show the others more clearly.

Referring now in detail to the drawings, 60 1 indicates the underframe and 2 the car body, both of which may be of any suitable construction and may be connected together in any suitable manner. The underframe as illustrated in the drawings comprises end 65 sills 3, side sills 4, bolsters 5 and draft sills 6, all of which may be of any suitable form. 7 indicates a platform plate which is secured to the end sill 3, side sills 4, bolster 5 and draft sills 6, and serves to connect these 70 members of the underframe rigidly together. 8 indicates angular members which extend from bolster to bolster and are spaced inwardly away from the side sills and away 75 from each other. At their ends these members are secured to the platform plates 7, and at intervals intermediate their ends are connected with short transverse members 9, one end of each of which members is secured to one of the side sills 4.

The body of the car comprises connected side and end walls 10 and 11 respectively. The upper portions 12 of the side walls are sloped downwardly and inwardly toward the longitudinal center line of the car, while 80 the lower portions 13 are disposed vertically and throughout their lengths are secured to the angular members 8. The upper portions 14 of the end walls are sloped downwardly and inwardly toward the transverse center 85 line of the car, while the lower portions 15 are disposed vertically. At substantially the transverse center line of the car, a transverse wedge 16 is provided which comprises plates 17, which extend between and are secured to the vertical portions 13 of the side walls. These plates are spaced apart for the greater portion of their depth and at their upper edges are secured together by rivets or other suitable means. At each end 90 of the car the lower portions of the side and end walls and one of the plates 17 of the transverse wedge 16, define a discharge opening 18 in the bottom of the car, which opening is closed by doors 19, which are 100 preferably bodily movable, and which have their meeting edges at substantially the longitudinal center line of the car. To stiffen 105

and support the body of the car, posts 20 and diagonal braces 21 are provided which at their lower ends are secured to the side sills 4 and at their upper ends are connected 5 with the upper edge portions of the body through the medium of gusset plates 22. At the end of the body, posts 23 are provided which at their lower ends are secured to the draft sills, and at their upper ends are connected 10 with the upper portion of the end wall. To further brace the end of the body, diagonally extending members 24 are provided which are secured at their lower ends to the underframe, and at their upper ends are connected 15 with the upper end portions of the end wall. 25 indicates a member which extends transversely of the car and serves to stiffen the car body and the underframe. This member is preferably of channel form, and at its ends is secured to the side sills 4. Intermediate its ends, the web of this member is secured to the vertically disposed portion 15 of the end wall.

Each of the doors 19 is provided at one 25 end with a suspension link 26, which is pivotally mounted in a bracket member 27 secured to the vertical portion of the end wall, and at the opposite end is provided with a similar link 28 which is pivotally mounted 30 in a bracket member 29 to one of the plates 17 of the transverse wedge 16. It will here be noted that the bracket members 27 and 29 are located a sufficient distance above the doors so that when the links 26 and 28 are 35 mounted therein, the doors will be permitted to move bodily and substantially clear of the door opening, thus facilitating the free and rapid discharge of the lading.

To operate each pair of discharge doors 40 a mechanism is provided which may be operated either by hand or fluid pressure means. This mechanism comprises a shaft 30 which extends transversely of the car and at its ends is journaled in bearing members 45 31, each of which is secured to one of the side posts 20, and intermediate its ends this shaft is journaled in bracket members 32, which are secured to the end posts 23. The shaft is provided with arms 33, each 50 of which is pivotally connected with the end portion 34 of a longitudinally extending link 35, the end portion 36 of such link being pivotally connected with the arm 37 of a bell crank 38, which is mounted on a 55 shaft 39 journaled in bearing members 40 and 41, the bearing member 40 being secured to the side wall 10, and the bearing member 41 being secured to one of the side posts 20. The arm 42 of the bell crank is pivotally connected with the upper end 43 of a 60 downwardly depending link 44, the lower end 45 of such link being pivotally connected with a toggle mechanism 46, which mechanism comprises links 47 and 48 having their adjacent ends operatively hinged

70 together by means of a pin 49 or other suitable means. This toggle mechanism extends between the side sill and the door, the end portion 50 of the link 47 being mounted on a shaft 51 that is journaled in bearing members 52, which are secured to the side sill and the transverse members 9 of the underframe, and the end portion 53 of the link 48 being pivotally connected with the door. For the purpose of operating the discharge 75 door operating mechanism by hand power, an operating shaft 54 is provided which has a gear wheel 55 mounted thereon, the teeth of which are adapted to mesh with the teeth of a quadrant 56 secured to the shaft 30. 80 For the purpose of operating this mechanism by fluid pressure, motors 57 and 58 are provided which are operatively connected together.

The motor 57 comprises a cylinder 59, 85 which is secured to the plate 7 or any other suitable part of the car, piston 60 and piston rod 61, such piston being secured to one end of the piston rod and arranged to reciprocate in the cylinder. The opposite end of the piston rod is mounted in an opening 62 formed in a bearing member 63, which is secured to the plate 7, or any other suitable part of the car. Intermediate the bearing member 63 and the 90 cylinder 59 the piston rod 61 is preferably provided with an enlarged portion 64, with which an arm 65 secured to the transverse shaft 30, is operatively connected by a pin 66, or other suitable means, which preferably passes through openings formed in the arm 65, and the enlarged portion 64 of the piston rod. It will be noted that when the 95 door operating mechanism is being operated, the arm 65 moves in an arc of a circle 100 and the piston rod 61 moves in a straight line, thus making it necessary to provide a loose connection between the arm and piston rod to insure the free operation of the mechanism. The object may be attained in a 105 number of ways but in the present embodiment of the invention is preferably attained by making the opening in the piston rod of slotted form having a width greater than the diameter of the pin 66, which passes 110 therethrough and a length great enough to permit of the maximum movement of the arm 65.

The motor 58 is arranged to operate at 115 an angle to the motor 57, and comprises a cylinder 67 which is secured to the plate 7 or any other suitable part of the car, and also comprises a piston 68 and piston rod 69, such piston being secured to one end of the piston rod and arranged to reciprocate 120 in the cylinder. The opposite or outer end portion 70 of this piston rod is preferably of rectangular form and preferably extends through the bearing member 63 at an angle 125 to the piston rod 61, and as indicated at 71 130

is adapted to extend across the path of travel of the piston rod 61 and form a stop or abutment therefor, thus locking the mechanism as a whole against accidental operation. This rectangular portion 70 of the piston rod 69 has an opening 72 formed therein which is larger than the end portion of the piston rod 61, which opening may be of any suitable shape. When the piston 10 rod 69 has been moved to the position as shown in dot and dash lines in Fig. 6 of the drawings, it will be noted that the opening 72 registers with the opening 62 of the bearing member 63, thus permitting the end portion 15 of the piston rod 61 to pass through the outer end portion 70 of the piston rod 69 and through the bearing member 63. For the purpose of operating the piston rod 69 by hand power a pivoted lever 73 is provided, one arm of which extends to the side of the car where it may be easily operated when it is desired to operate the whole mechanism by use of the shaft 54. The other arm of this lever is connected 20 with one end of a link 74, the opposite end of such link being loosely connected with the piston rod 69, such connection being preferably made by bending the end portion of the link 74 in the form of a hook which 25 extends through a slot 75 formed in the outer end portion of the piston rod 69.

76 indicates a pressure supply pipe which extends preferably from end to end of the car and may be provided with cocks 77. 30 Between these cocks and at each end of the car this supply pipe is provided with a branch pipe 78 which is connected with a port 79 formed in the cylinder 67. Some distance from the port 79 the cylinder is 35 provided with a port 80 which is connected with a port 81, formed in the cylinder 59, by a pipe 82. This cylinder 67 is also provided with an outlet 83 to the atmosphere, the use of which will hereinafter be described. 40 84 indicates another pressure supply pipe which extends preferably from end to end of the car and may be provided with cocks 85. Between these cocks and at each end of the car, the supply pipe 84 is provided with a branch pipe 86 which is connected with a port 87 formed in the cylinder 59.

When it is desired to automatically open the discharge doors one of the cocks 77 is 45 closed and a pipe or hose from the fluid pressure supply is attached to the other cock 77 which is open. Fluid pressure is then introduced which enters the cylinder 67 through the supply pipe 76 and branch pipe 50 78 and moves the piston 68 and piston rod 69 a sufficient distance to slide the opening 72 in the portion 70 into registration with the opening 62 in the bearing member 63. Immediately after the opening 72 has registered 55 with the opening 62, the piston 68

passes the port 80, permitting the pressure to enter the cylinder 59 through the pipe 82, and move the piston 60 in the direction indicated by the arrows in Fig. 4 of the drawings a sufficient distance to fully operate the door operating mechanism. When the piston 60 is being moved in this direction by the fluid pressure, the air in the cylinder on the other side of the piston is allowed to escape to the atmosphere through 70 the pipes 86 and 84. Between the port 80 and the outlet 83, the cylinder 67 is provided with a portion 88 which forms a stop for the piston 68 when such piston has passed the port 80, thus preventing the piston from 75 passing the outlet 83 and the escape of the pressure through such outlet.

When the piston 60 is moved in the direction referred to above, the end portion of the arm 65 is moved in the same direction 80 through the intervention of the piston rod, which connects the piston and arm, with the result that the arms 33, 33, which are secured to the shaft 30, are caused to move in the opposite direction, and through the medium of the links 35, 35 cause the bell cranks 38 to raise the links 44, 44. These links 44, 44 are connected with the toggle mechanism 46, 46 and when they are raised by the bell cranks 38, they will move the 90 links of the toggle mechanisms and the discharge doors to the positions as shown in dot and dash lines in Fig. 3 of the drawings.

When it is desired to automatically close the doors, one of the cocks 85 is closed and 100 a pipe or hose from the fluid pressure supply is attached to the other cock 85 which is open. Fluid pressure is then introduced through the supply pipe 84 and branch pipe 86 to the cylinder 59, which forces the piston 60 in a direction opposite to that indicated by the arrows in Fig. 4 of the drawings, the air on the other side of the piston being permitted to escape to the atmosphere through the pipe 82 and outlet 83 in the 110 cylinder 67. The operation of the rest of the mechanism, when the doors are being closed, is the reverse of that just described in connection with the opening of the doors.

Within the cylinder 67, a spring 89 is 115 provided which when the doors are being opened will, by the movement of the piston 68, be compressed, and which when the doors are being closed, will expand and force the piston 68 and piston rod 69 to their normal 120 positions of rest, as shown in full lines in Figs. 5 and 6 respectively. When the doors are being opened by the use of fluid pressure the piston 68 moves forward until it engages the stop 88 in the cylinder at which time 125 the portion 70 of the piston rod 69 is in the position as shown in dot and dash lines in Fig. 6, the piston and piston rod remaining in such positions until the doors have been opened. After the doors have been 130

opened and the fluid pressure shut off, the spring 89 will force the piston 68 backward beyond the port 80 to a position, as shown in dotted lines in Fig. 5, thus permitting 5 the exhaust pressure from the cylinder 59 when the doors are being closed, to escape to the atmosphere, through the outlet 83, the slot 72 in the piston rod 69 being of a length great enough to permit such movement 10 of the piston 68 relative to the port 80. When the doors are closed and when the end of the piston 60 has been drawn from the opening 72 in the piston rod 69, the spring 89 will force the piston 68 backward 15 to its normal position of rest, as shown in full lines in Fig. 5, and will thus move a portion of the piston rod 69 across the opening 62 in the bracket member 63, which will prevent accidental movement of the piston 20 rod 61 and will thus lock the mechanism against accidental operation.

When it is desired to operate the mechanism by hand power, the operator moves the lever 73 in the direction as indicated 25 by the arrow in Fig. 4 and such lever being pivoted as indicated at 90 will cause the portion 70 of the piston rod 69 to move a sufficient distance to unlock the mechanism, the maximum movement of the piston being 30 shown in dotted lines in Fig. 5. The shaft 54 is then rotated in the direction as indicated by the curved arrow in Fig. 2 and the gear wheel 55 mounted on this shaft meshing with the toothed quadrant 56 35 mounted on the shaft 30, will cause the mechanism to operate in the same manner as hereinbefore described. It will here be noted that by reason of the loose connection between the lever 73 and the portion 70 40 of the piston 69, the piston when it is being operated by fluid pressure will be permitted to move independently of the lever 73, thus rendering the fluid pressure unlocking mechanism entirely automatic.

45 It will be seen from the foregoing description of the mechanism that the doors of a train of cars may be operated automatically and substantially simultaneously. By connecting the cocks 77 and 77 of adjacent cars, 50 closing one of the cocks 77 at one end of the train, and then admitting pressure through the other cock at the opposite end of the train, the operation of the mechanism as hereinbefore described in connection with a 55 single car, will be repeated throughout the train of cars, and the doors of all the cars will be opened simultaneously or nearly so. By connecting the cocks 85 and 85 of adjacent cars, closing one of the cocks 85 at one 60 end of the train and then admitting pressure through the other cock 85 at the opposite end of the train, the operation of the mechanism will be repeated throughout the train of cars and the doors of all the cars will be closed 65 simultaneously or nearly so. In operating

a train of coupled cars embodying the invention, it may be desired to discharge the loading from certain of the cars and to leave the remaining cars of the train loaded so that they can be moved and discharged at some other place. In order to do this the branch pipes 78 of each car are provided with cocks 91 by means of which the fluid pressure supply may be shut off from the discharge door operating mechanisms of the car or cars 75 that it is not desired to discharge. By this means it is possible to discharge the load from any one car or series of cars in a train and at the same time retain the load in the remaining cars of the train. The branch 80 pipes 86 of each car is provided with cocks 92 by means of which the fluid pressure may be shut off from the discharge door operating mechanism of a car or cars that it is not desired to close the doors. The car as hereinbefore described is provided with two pairs of doors which are operated by two pairs of 85 motors, one pair of motors being for one pair of doors. It may be found desirable to discharge only a portion of the contents of the car, and to do this, one of the cocks 91 is closed and the other one opened, thus permitting one pair of motors to operate to open one pair of doors only. When a plurality 90 of cars, embodying the invention, are coupled together, it will be noted, the whole contents of some of the cars may be discharged and that only a portion of the contents of other cars may be discharged, while the contents of the remaining cars may be retained and 95 discharged at some other places.

From the foregoing description it will be apparent that changes may be made in the arrangement and construction of the parts of the mechanism without departing from 105 the spirit and scope of the appended claims.

Having thus described the invention what I claim as new and desire to secure by Letters Patent is:

1. In a railway dump car, a discharge door 110 operating mechanism, and a plurality of pairs of operatively connected motors for operating said mechanism, one of the motors of each pair being adapted to time the action of the other motor of each pair, and locking means slidably by one of the motors of each pair into and out of engagement with the other of said motors of each pair.
2. In a railway dump car, a discharge door 120 operating mechanism, and a plurality of pairs of motors for operating said mechanism, one motor of each pair being so constructed and connected to the other motor of each pair that it will operate in advance of said other motor, and means slidably by 125 one of the motors of each pair into and out of engagement with the other of said motors of each pair to lock and unlock said mechanism.
3. In a railway dump car, a discharge door 130

- operating mechanism and fluid pressure means for automatically operating said mechanism, said means comprising a plurality of pairs of operatively connected motors, and means slidably into engagement with one of the motors of each pair to lock said mechanism.
4. In a railway dump car, discharge doors and a plurality of pairs of operatively connected fluid pressure motors for automatically operating said doors, and means slidably into and out of engagement with one of the motors of each pair to lock and unlock said doors.
5. In a railway dump car, a discharge door a fluid pressure motor, connections from said door to said motor, a member slidably across the path of operation of said motor, and a motor for operating said member.
6. In a railway dump car, a discharge door, a fluid pressure motor, means connecting said door and motor, a slidable member for locking said means, and a fluid pressure motor for operating said member.
7. In a railway dump car, a plurality of discharge doors, a motor connected with said doors for automatically opening and closing them, slidable means for holding said doors in closed position, and a motor for operating said means.
8. In a railway dump car, a plurality of discharge doors, a pair of operatively connected motors for operating said doors, said motors comprising piston rods and arranged to operate at an angle to each other, the piston rod of one of said motors having an opening formed therein through which the piston rod of the other motor passes when the doors are being opened.
9. In a railway dump car, a plurality of discharge doors, a plurality of operatively connected motors for operating said doors, each of said motors comprising a piston rod, said motors being arranged to operate at an angle to each other, the piston rod of one of said motors being movable into and out of the path of travel of the piston rod of the other of said motors to lock and unlock said doors.
10. In a railway dump car, a plurality of discharge doors, toggle mechanisms for operating said doors, a shaft extending transversely of said car, connections from said shaft to said toggle mechanisms for operating said mechanisms, a motor for operating said shaft, and a motor adapted to operate in advance of and time the action of the first mentioned motor, the last mentioned motor having a piston rod adapted to engage with the first mentioned motor to lock said doors in their closed positions.
11. In a railway dump car, a discharge door, mechanism for operating said door, a motor for operating said mechanism, said motor comprising a piston rod, means with which said piston rod is adapted to engage to lock said door in its closed position, and a motor operatively connected with the first mentioned motor for moving said means out of the path of said piston rod when the door is being opened or into the path of said piston rod when the door is closed.
12. In a railway dump car, a pair of discharge doors, mechanism for operating said doors, a motor for operating said mechanism, said motor comprising a piston rod, a bearing member for said piston rod, means mounted in said bearing member slidably into and out of the path of said piston rod, and a motor for operating said means.
13. In a railway dump car, a pair of discharge doors, mechanism for operating said doors, a motor for operating said mechanism, said motor comprising a piston rod, a motor operatively connected with the first mentioned motor, said motor comprising a piston rod adapted to be moved into and out of the path of the first mentioned piston rod, and means within the second mentioned motor for timing the action of the first mentioned motor so that the second mentioned piston rod will be operated in advance of the first mentioned piston rod.
14. In a dump car discharge door operating mechanism, a plurality of operatively connected motors for operating said mechanism, each one of said motors comprising a piston rod, the piston rod of one of said motors being movable into and out of the path of the piston rod of the other of said motors to lock and unlock said other motor.
15. In a dump car discharge door operating mechanism, a plurality of operatively connected motors for operating said mechanism, each one of said motors comprising a pressure cylinder and a piston rod, and a bearing member secured to said car having openings formed therein at an angle to each other, the piston rod of one of said motors being slidably mounted in one of said openings and the piston rod of the other of said motors being slidably mounted in the other of said openings, one of said piston rods being movable in said bearing member into and out of the path of the other of said piston rods.
16. In a dump car discharge door operating mechanism, a plurality of operatively connected motors for operating said mechanism, each one of said motors comprising a pressure cylinder and a piston rod, and a bearing member secured to said car having openings formed therein at an angle to each other, the piston rod of one of said motors being slidably mounted in one of said openings and the piston rod of the other of said motors being slidably mounted in the other of said openings, one of said piston rods having an opening formed therein through which the other of said piston rods is adapt-

- ed to pass, said openings being adapted to register with one of the openings in said bearing member.
17. In a dump car discharge door operating mechanism, a motor for operating said mechanism, said motor comprising a pressure cylinder and a piston rod, means slideable into and out of the path of said piston rod for locking and unlocking said mechanism, and means for operating the first mentioned means.
18. In a dump car discharge door operating mechanism, a motor for operating said mechanism, said motor comprising a pressure cylinder and a piston rod, a member slideable into and out of the path of said piston rod for locking and unlocking said mechanism, and fluid pressure means for operating said member.
19. In a dump car discharge door operating mechanism, a motor for operating said mechanism, said motor comprising a pressure cylinder and a piston rod, a member slideable into and out of the path of said piston rod for locking and unlocking said mechanism, and fluid pressure means and lever means for operating said member.
20. In a dump car discharge door operating mechanism, a motor for operating said mechanism, said motor comprising a pressure cylinder and a piston rod, a motor for timing the action of the first mentioned motor, the second mentioned motor comprising a pressure cylinder and a piston rod, said piston rod being movable out of the path of the first mentioned piston rod by means of fluid pressure and movable into the path of said piston rod by means independent of the fluid pressure.
21. In a dump car a plurality of pairs of discharge doors, mechanism for operating said doors, and a plurality of pairs of operatively connected motors for operating said mechanism, means movable by one of the motors of each pair into and out of engagement with the other of the motors of each pair to lock and unlock said doors and mechanism, a pressure supply pipe extending from end to end of the car, a branch pipe extending from said supply pipe to one of the motors of each pair of motors, and a valve in said branch pipe for shutting off the pressure from said motor for rendering each of said pairs of motors inoperative.
22. In a railway dump car, a pair of bodily movable discharge doors, toggle mechanisms for operating said doors, a rotatable shaft extending transversely of said car, connections from said shaft to said toggle mechanisms, an arm on said shaft, a motor having a piston rod loosely connected with said arm for operating said shaft, means adapted to be moved into and out of engagement with said piston rod to lock and unlock said doors, a motor and a hand lever for operating said means, a rotatable shaft for manually operating the first mentioned shaft and means for operatively connecting said shafts.
23. In a railway dump car, a pair of discharge doors, a rotatable shaft extending transversely of said car, connections from said shaft to said doors, an operating motor comprising a piston rod, connections from said piston rod to said shaft, an operating shaft, connections from said operating shaft to said rotatable shaft, means movable into and out of the path of said piston rod for locking and unlocking said doors, and a motor and hand lever for operating said means.
24. In a dump car discharge door operating mechanism, means for operating said mechanism, said means comprising a piston rod, means for operating said piston rod by hand power, a member movable into and out of the path of said piston rod, a hand lever for moving said member out of the path of said piston rod, and means for automatically moving said member into the path of said piston rod.
25. In a dump car discharge door operating mechanism, a motor for operating said mechanism, said motor comprising a cylinder and a piston rod, a member movable into and out of the path of said piston rod for locking and unlocking said mechanism, a motor for operating said member, and a hand lever for operating said member, said lever being loosely connected with said member to permit the free movement of said member independent of said lever.
26. In a dump car discharge door operating mechanism, means for operating said mechanism, said means comprising a piston rod, means slideable into and out of the path of said piston rod for locking and unlocking said mechanism, a lever for moving said slideable means out of the path of said piston rod and means independent of said lever for automatically moving said member into the path of said piston rod.
